US00D805027S

(12) **United States Design Patent** (10) **Patent No.:** **US D805,027 S**
Andre et al. (45) **Date of Patent:** **** Dec. 12, 2017**

(54) **BATTERY**

(71) Applicant: **Apple Inc.**, Cupertino, CA (US)

(72) Inventors: **Bartley K. Andre**, Palo Alto, CA (US);
Mikael Silvanto, San Francisco, CA (US); **David P. Tarkington**, Sunnyvale, CA (US); **Joshua Funamura**, San Jose, CA (US); **Ari Parsons Miller**, San Francisco, CA (US)

(73) Assignee: **Apple Inc.**, Cupertino, CA (US)

(**) Term: **14 Years**

(21) Appl. No.: **29/519,710**

(22) Filed: **Mar. 6, 2015**

(51) **LOC (10) Cl.** **13-02**

(52) **U.S. Cl.**

USPC **D13/103**

(57) **CLAIM**

The ornamental design for a battery, as shown and described.

DESCRIPTION

FIG. 1 is a top perspective view of a battery showing our new design;

FIG. 2 is a bottom perspective view thereof;

FIG. 3 is a front view thereof;

FIG. 4 is a rear view thereof;

FIG. 5 is a left side view thereof;

(Continued)

FIG. 6 is a right side view thereof;
 FIG. 7 is a top view thereof; and,
 FIG. 8 is a bottom view thereof.

1 Claim, 6 Drawing Sheets
